No. 794,426.

PATENTED JULY 11, 1905.

G. SAALER.
TACHOMETER.
APPLICATION FILED NOV. 29, 1904.

UNITED STATES PATENT OFFICE.

GUSTAV SAALER, OF EMMENDINGEN, GERMANY, ASSIGNOR TO NIAGARA TACHOMETER AND INSTRUMENT COMPANY, OF NIAGARA FALLS, NEW YORK, A CORPORATION OF NEW YORK.

TACHOMETER.

SPECIFICATION forming part of Letters Patent No. 794,426, dated July 11, 1905.

Application filed November 29, 1904. Serial No. 234,737.

To all whom it may concern:

Be it known that I, GUSTAV SAALER, a subject of the German Emperor, residing at Em-
mendingen, Grand Duchy of Baden, Germany,
5 have invented certain new and useful Im-
provements in Tachometers; and I do hereby
declare the following to be a full, clear, and
exact description of the invention, such as will
enable others skilled in the art to which it ap-
10 pertains to make and use the same.

My invention relates to an improvement in
rotary speed-indicators of the same general
class as described in an application heretofore
filed on November 14, 1904.

15 My present invention is a modification there-
of; and it consists in a construction by which
the range of indication is much extended.

The essential features are two separated sub-
stantially equal containers for the mercury
20 arranged at equal distances from the vertical
axis of rotation. Each container is connected
by a very small hole to a cylindrical rising
chamber, the holes being at the extreme outer
edge of both container and rising chamber.

25 Each rising chamber is connected at its upper
end by a gradually-diminishing connecting-
tube to the vertical axially-arranged indicat-
ing-tube. A return-tube connected to the in-
dicating-tube at its top extends to about the
30 foot of the latter and is connected by branches
to the two containers. The containers are
nearly filled with mercury, and the rising
chambers, connecting-tubes, and branches
with a lighter liquid preferably to about or a
35 little above the foot of the indicating-tube.

Here the proportions are also important, but
different from those of the device of my said
application. In the invention here described
40 the total capacity of the rising chambers
should be at least equal (a slight excess is not
objectionable) to the capacity of the indicating
portion of the indicating-tube; but the con-
tainers are of such size that the total mercury
45 therein contained is substantially double the
total contents of both the rising chambers.
By this proportion and by the fact that there
is no large connection filled with mercury be-
tween the containers, which central bulk of

mercury would tend by its weight to force
the mercury adjacent to the holes outwardly, 50
and so upwardly, there is less force applied
to the mercury during rotation, and it rises
much more slowly and gradually in the rising
chambers and permits a wider range of indica-
55 tion from the lowest indicated speed to about
four times that speed (one to four)—for in-
stance, about from three hundred to twelve
hundred or, as indicated, about from two hun-
dred to eight hundred revolutions per minute.

It will be understood that for most rotating 60
objects—such as shafts, turbines, dynamos,
centrifugal separators, &c.—the best and most
economical speed for each particular machine
or location is approximately known, and there-
fore it is not generally necessary to measure 65
or indicate any wide range of speeds; but
where indicators for a wide range are desired
my present device is practical and well adapted.

My invention will be understood by refer-
ence to the drawings herewith, in which the 70
reference-numerals of the specification indi-
cate the same parts in all the figures.

Figure I is a front elevation of my indi-
cator or indicating vessel with an illustrative
scale arranged adjacent to the indicating-tube. 75
Fig. II is a side elevation. Figs. III and IV
are cross-sections of Fig. I on lines III and
IV, respectively. Fig. V shows a slight modi-
fication in form. Figs. VI and VII are re-
spectively vertical and cross sections of an 80
electrical alarm which may be used with my
speed-indicator of any construction.

In the figures, 11 indicate the two containers,
preferably circular in cross-section with flat
tops and in general form a short cylinder with 85
a hemispherical base, like the end of a test-
tube. Their depth is about equal to their
diameter. They are equal in size, as near as
may be, and arranged parallel and corre-
spondingly at equal distances from the axis. 90

22 are small holes connecting the respec-
tive containers to their rising chambers 33
and arranged at the extreme outer margins
of both—that is, at the greatest distance from
the axis of rotation. From one millimeter to 95
about two millimeters, as near as may be, are

- desirable sizes for the holes. If they are substantially above three millimeters in diameter, they would be too large and there would be danger of the lighter liquid flowing back during rotation. They are as small as can reasonably be made; but it will be understood that where the indicating vessel is blown from glass very slight variations cannot be avoided.
- 10 The preferably cylindrical rising chambers are united by connecting-tubes 55 to the foot of the indicating-tube 6, connecting at its upper end with the preferably larger return-tube 8, from whose lower end extend the large branch tubes 99 to the tops of the respective containers for the return of the lighter liquid accidentally overflowing. Each branch should be at least substantially as large in diameter as the indicating-tube.
- 15 The containers are nearly filled with mercury, leaving only a small space for the lighter liquid (preferably tinted) to connect the holes with the branches, so that the lighter liquid accidentally overflowing may flow back into the containers when the indicator is at rest.
- 20 This lighter liquid stands about at a level in the tubes about at the foot of the indicating-tube and a short distance below the foot of the scale, it being preferred that the scale should not extend to the foot of the indicating-tube, but leave a little space in which the lighter liquid will rise before it begins to indicate. On account of capillarity the lighter liquid may stand a little higher initially in the indicating-tube than in the return-tube. The scale may be stationary and inclosed in the outer glass tube 17 or in some cases inscribed directly on the return-tube, where that incloses the indicating-tube.
- 25 It will be understood that the indicating vessel here described and shown in Figs. I to V may be made of glass in one piece and may be inclosed in a shell and mounted in a case provided with means for connecting it to the rotating object, all as described in my former application. The only difference in the device of Fig. V is that the branch is extended as a single tube down to or nearly to the level of the container, where it divides, and therefore its upper portion must be of larger capacity.
- 30 The electrical alarm (shown in Figs. VI and VII) may be applied to any similar tachometer. It consists of a cap 30, of insulating material, secured on the indicating-tube and having a bearing 21 in cap 19 on outer glass tube 17, which is part of the case in which the indicator is inclosed. This cap 30 is provided with an axial chamber 31 and outer chambers 32, connected above and below and containing mercury or other electrically-conducting liquid of an amount proportioned to the speed at which the alarm is to be given. Chambers 32 should be equal and at equal distances from the center.

33 is a lower metallic band in constant connection by plugs with the mercury, and 34 is an upper band, also having plugs which enter the outer chambers and make connection with the mercury when it is raised along the outer sides of the outer chambers by a sufficient centrifugal force, then closing the circuit and giving the alarm that an undesirable speed has been reached.

37 and 38 are spring-contacts fixed in cap 19 and respectively in contact with bands 33 and 34. Here cap 19 must be of insulating material or the spring-contacts be insulated therefrom, as by suitable bushings. The contacts are connected by wires to bell or other suitable alarm, which is sounded when the circuit is closed by the rise of the mercury into contact with the plugs of upper band 34.

The chambers in the cap are preferably small, that the mercury may move up and down uniformly and gradually. If the chambers were large, the mercury would tend to be forced up rapidly and fall slowly, which would cause inaccuracy in the alarm.

Having thus described my invention, what I claim as new, and desire to secure by Letters Patent, is—

1. As a new article of manufacture, an indicating vessel for a tachometer, said vessel being adapted to be rotated on a vertical axis and having in combination two containers, a rising chamber connected to each container, an indicating-tube connected to the rising chambers, and return connections from the upper portion of the indicating-tube to the containers.

2. As a new article of manufacture, an indicating vessel for a tachometer, said vessel being adapted to be rotated on a vertical axis and having in combination two similar containers, a rising chamber connected to each container, an indicating-tube connected to the rising chambers, and return connections from the upper end of the indicating-tube to the upper portions of the containers, the capacity of each container being not substantially less than twice the capacity of each rising chamber.

3. In a tachometer, a closed indicating vessel made entirely of glass and adapted to rotate on a vertical axis, said vessel having in combination a plurality of similar, separated containers, of uniform size and uniformly arranged at substantially equal distances from the axis of rotation, each container being circular in cross-section and having its diameter and depth substantially equal, a cylindrical vertical rising chamber arranged on each container and connected thereto by a small hole adjacent to the outer wall of the container and the rising chamber, an indicating-tube arranged in the axis of rotation and having an open upper end, connecting-tubes connecting the indicating-tube at its foot to the upper ends of the rising chambers, a return-

tube inclosing the indicating-tube, a branch connecting the foot of the return-tube with the tops of the respective containers, mercury nearly filling each container, and a lighter liquid resting on the mercury and filling the vessel about to the foot of the indicating-tube, the total capacity of the rising chambers being not substantially less than the capacity of the indicating-tube and each container being 10 of about twice the capacity of each rising chamber.

4. As a new article of manufacture, a glass indicating vessel for a tachometer, having in combination a plurality of substantially equal 15 containers, symmetrically arranged with reference to the axis of rotation, a rising chamber connected to each container, an indicating-tube connected to the rising chambers and return connections from the upper end of the 20 indicating-tube to the containers.

5. A glass indicating vessel for a tachometer having in combination a plurality of substantially equal containers, a rising chamber connected to each container, a single indicating-tube connected at its lower end to the upper 25 ends of all the rising chambers, return connections from the upper end of the indicating-tube to the containers, mercury nearly filling the containers and a lighter liquid above the 30 mercury filling the vessel about to the foot of the indicating-tube, the containers being of such a size that the amount of mercury therein contained shall not be less than twice the capacity of all the rising chambers, and not 35 less than twice the capacity of the indicating-tube.

6. A glass indicating vessel for a tachometer, having in combination two equal containers, in the form of short cylinders, vertically arranged, having substantially semiglobular 40 bases, a rising chamber on each container and connected thereto by a small hole, an indicating-tube connected to the rising chambers and return connections from the upper end of the 45 indicating-tube to the containers.

7. A one-piece, closed, glass indicating ves-

sel for a tachometer, adapted to be rotated on a vertical axis, and having in combination two substantially equal containers, symmetrically arranged with reference to the axis, each container being in the form of a vertically-arranged, short cylinder having substantially a semiglobular base, a cylindrical rising chamber on each container and connected thereto by a small hole, an indicating-tube arranged 50 above the rising chambers and having its lower end connected to the upper ends of said chambers, and return connections from the upper end of the indicating-tube to the tops of the 55 containers, the rising chambers being substantially equal in total capacity to the indicating-tube and the total capacity of the containers being substantially double the capacity of all the rising chambers.

8. In a tachometer, a glass indicating vessel 60 adapted to be rotated on its vertical axis and having in combination containers symmetrically arranged with reference to the axis, rising chambers arranged on the containers and connected therewith by holes arranged adjacent to the outer walls, said holes being not less than one millimeter and not substantially more than three millimeters in diameter, an indicating-tube, having an open upper end, arranged in the axis of rotation and connected 65 to the upper ends of the rising chambers, a return-tube extending from the open upper end of the indicating-tube down adjacent to the lower end of the indicating-tube, a branch 70 connecting the lower portion of the return-tube with the upper portion of the containers, mercury nearly filling the containers, and a lighter liquid resting on the mercury and filling the various parts of the vessel about to the 75 foot of the indicating-tube substantially as described and shown.

In testimony whereof I affix my signature in presence of two witnesses.

GUSTAV SAALER.
